UNITED STATES PATENT OFFICE.

GUY L. BONHAM, OF WEST HARTFORD, CONNECTICUT.

SAFETY-RAZOR.

1,264,605.

Specification of Letters Patent. Patented Apr. 30, 1918.

Application filed February 21, 1917. Serial No. 150,235.

To all whom it may concern:

Be it known that I, GUY L. BONHAM, a citizen of the United States, residing at West Hartford, in the county of Hartford 5 and State of Connecticut, have invented a new and useful Safety-Razor, of which the following is a specification.

The present invention appertains to safety razors of the rotary head type, such as disclosed in my patent on safety razor No. 1,093,102 granted April 14, 1914 and my patent on revolving safety razor and massage mechanism, No. 1,158,781 granted November 2, 1915.

15 It is the object of the invention to provide a novel and improved rotary head for a safety razor of the character indicated, said head having novel means for properly and effectively holding the razor blades, in order 20 that their edges will be properly presented to the hairs.

Another object of the invention is the provision of novel means for clamping double-edged flexible blades to the head with their 25 edges in helical lines, and with the blades clamped firmly in place between their edges, the blades being readily removed and replaced.

The invention also has for its object the 30 provision of the improvements above noted and involving a simple, compact and inexpensive construction, which is practical and efficacious in use.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed, can be made within the scope of what is claimed, without departing from the spirit of the invention.

The invention is illustrated in the accompanying drawings, wherein:—

Figure 1 is a perspective view of one form of the invention.

Fig. 2 is a section on the line 2—2 of Fig. 1, the parts being shown as if they were longitudinal, for sake of clearness.

Fig. 3 is a cross section taken on the line 3—3 of Fig. 1.

Fig. 4 is a reduced perspective view of the locking plate or slide.

Fig. 5 is a reduced plan view of one blade. 55

Fig. 6 is a view similar to Fig. 1 of another form of the invention.

Fig. 7 is a section on the line 7—7 of Fig. 6.

Fig. 8 is a reduced plan view of one of 60 the blades used in the second form.

Fig. 9 is a reduced perspective view of one of the clamping plates used in the second form.

Fig. 10 is a perspective view of a third 65 form of the invention.

Figs. 11 and 12 are sections on the respective lines 11—11 and 12—12 of Fig. 10, similar to Figs. 2 and 3.

Fig. 13 is a reduced plan view of one of 70 the blades used in the third form.

Fig. 14 is a reduced perspective view of one of the clamping plates used in the latter form.

The head 1 is adapted to be mounted for 75 rotation within a suitable casing or guard, as disclosed in the above mentioned patents, and since the improvements reside in the head, the guard, actuating mechanism and other parts are not illustrated or described. 80 The head 1 embodies the end pieces 2 connected by the helical blade supports or beds 3 of arcuate cross section having their convexed surfaces facing outwardly. As illustrated, there are two of the supports 3, although any suitable number can be used. Each support 3 is provided near its ends and between its edges with apertures or 85 openings 4, although any suitable number of apertures can be used in any desired arrangement. The support 3 is also provided adjacent to its ends with outstanding stay pins or lugs 5.

A helical flexible or resilient razor blade 6 is adapted to rest against and conform to 95 the curvature of each support 3, and is provided with opposite cutting edges 7 which project beyond the edges of the support 3 since the blade is of greater width than the support. The blade 6 is provided with apertures or openings 8 coinciding or registering with the apertures 4, and the blade is also provided near its ends with apertures 9 for receiving the lugs 5, whereby to hold the blade in proper position and prevent its displacement when applied to the support.

Each blade is clamped against its support 3 by means of a helical clamping plate 10 is

substantially the same width as the support and having its inner surface of the same curvature as the support, whereby the plate 10 in being drawn slightly toward the support 3 will flex the blade 6 between the support and plate 10, and the blade will be clamped between said support and plate. The plate 10 is provided upon its inner side with a channel or elongated recess 11 between its edge portions, in order that only the edge portions will bear against the blade 6 for flexing the edge portions of the blade against the support 3.

The clamping plate 10 is held in place by means of studs or shanks 12 projecting inwardly from its intermediate portion within in the channel 11 between its edge portions and insertable inwardly through the apertures 8 and 6 of the blade and support when the plate 10 is applied, the studs or shanks 12 having heads 13 to move through said apertures. A helical locking plate or member 14 is slideable along the inner surface of each support 3, the support 3 having inwardly bent back flanges or lips 15 providing guide slots in which the edge portions of the plate 14 are slideable. One end piece 2 of the head has a slot or opening 16 through which one end portion of the plate 14 is slideable, and said projecting end of the plate 14 has an inwardly bent ear or finger piece 17 whereby the plate 14 can be pulled outwardly and pushed inwardly. The plate 14 is provided near its ends and between its edges with key-hole shaped openings or apertures 18, and the plate 14 is indented around the tails of the apertures 18, as at 19.

In assembling the parts, the locking plate 14 is pulled outwardly until the heads of the apertures 18 register with the apertures 4, the blade 6 then being applied to the support 3 and being held in place by the studs or pins 5, after which the clamping plate 10 is applied with its shanks or studs 12 projecting through the registering apertures 8, 4 and 18. The channel 11 accommodates the lugs or pins 5 which project through the apertures 4. The heads 13 move through said apertures to the inner side of the locking plate 14, and said locking plate is then pushed inwardly, so that the heads of the apertures 18 are moved away from the apertures 4 and the tails of the apertures 18 engaged with the shanks or studs 12. The indentations or inwardly projecting cam portions 19 will engage the heads 13 and force them inwardly by a cam action, thus drawing the plates 10 tightly into place to firmly clamp the blades 6 between the supports 3 and clamping plates 10. In this manner, the blades 6 of the head are firmly held in place in helical positions, with their cutting edges 7 in similar positions. The cylindrical path of movement of the cutting edges 7 is outside of the outer convexed surfaces of the

clamping plates 10, since the curvatures of the inner surfaces of the plates 10 and the supports 3 are eccentric, and the radii of said curvatures are of greater length than the radius of said path of rotation. The blades can be readily removed by pulling the locking plates 14 outwardly, thereby enabling the heads 13 to pass through the heads of the apertures 18 for removing the clamping plates 10, which in being removed permit the blades to be detached for sharpening and replacement.

In the modified construction illustrated in Figs. 5 and 6, each support 3 is provided with elongated slots or apertures 4', and the blade 6 has similar slots or apertures 8' to register therewith, while the clamping plate 10 is provided with inwardly projecting hooks 13' to move through said apertures 8' and 4'. The support 3 is preferably provided with thickened portions or bosses 19' upon its inner surface for the engagement of the hooks 13' whose bills are inclined. The outer surface of the clamping plate 10 can be knurled or roughened in order that said plate can be readily shifted lengthwise of itself after the hooks 13' are inserted through the apertures 8' and 4', thus forcing the bills of the hooks with a cam action against the bosses 19', for drawing the clamping plate 10 inwardly to tightly clamp the blade 6 against the support 3. This form requires the longitudinal movement of the clamping plate 10, but eliminates the locking plate 14.

The form illustrated in Figs. 7, 8 and 9 embodies the longitudinal movement of the clamping plates 10, but eliminates the hooks 13' which are objectionable for certain uses, since they are more apt to bend or break than the headed studs 12 which are used in the third form instead of the hooks. The support 3 and blade 6 are provided with key-hole shaped apertures 4'' and 8'', respectively, which register with one another, for the insertion of the studs 12 therethrough, and the support 3 has studs 19'' surrounding the tails of the apertures 4'' in order that when the heads 13 are inserted through said apertures and the plate 10 forced longitudinally, the heads 13 will ride onto the studs 19'' with a cam action for forcing the plate 10 inwardly to tightly grip the blade.

The rotary head when actuated within a suitable guard will effectively sever the hairs, and the edges 7 of the plates being disposed helically will cut the hairs with a diagonal stroke. A razor of this type has many advantages over the ordinary razors.

Having thus described the invention, what is claimed as new is:

1. A razor embodying a transversely curved support having apertures and lugs projecting from its convex side, a blade

resting against the convex side of the support and having apertures to register with the aforesaid apertures and other apertures for the projection of said lugs therethrough,
5 and a plate to clamp the blade against the support and having an inner longitudinal channel providing portions at opposite sides thereof, to bear against the blade, said channel accommodating said lugs, the clamping
10 plate having studs projecting therefrom within said channel through said registering apertures, and said studs and support having means interengageable by relative sliding movement and cam action for drawing
15 the plate toward the support.

2. A razor embodying a support having bent back edges, a member slideable along the support and guided by said edges, a blade resting against the support opposite
20 said member, and a clamping plate resting against the blade and having means extending through said blade and support and en-

gageable with said member when the same is slid, to clamp the parts together.

3. A razor embodying a blade support, 25 having bent back edges providing guides, a member slideable along one side of said support within said guides, a blade resting against the other side of said support, and a clamping plate resting against the blade 30 and having studs provided with heads, said blade, support and member having apertures for the passage of said studs, and said member having cam portions engageable with said heads by a sliding movement to 35 clamp the parts together.

In testimony that I claim the foregoing as my own, I have hereto affixed my signature in the presence of two witnesses.

GUY L. BONHAM.
